United States Patent Office

Des. 219,349
Patented Dec. 1, 1970

219,349

KETTLE OR SIMILAR ARTICLE

Henry Muller, New York, N.Y., assignor to Cathrineholm
Ltd., Norwalk, Conn., a corporation of New York

Filed Jan. 2, 1970, Ser. No. 20,744

Term of patent 14 years

Int. Cl. D7—02

U.S. Cl. D44—25

Fig. 1

Fig. 2

Fig. 3

Fig. 4

FIG. 1 is a side elevational view of a kettle showing my new design;

FIG. 2 is a front elevational view thereof;

FIG. 3 is a top plan view thereof showing the handle portion in horizontal position; and

FIG. 4 is a bottom plan view thereof, showing the handle in similar position.

I claim:

The ornamental design for a kettle or similar article, substantially as shown.
